[57] CLAIM

The ornamental design for a shoe heel protector, as shown.

DESCRIPTION

FIG. 1 is an illustrative view and FIG. 9 is an illustrative rear elevational view in a position of use, respectively. The broken line showing of the shoe sole in FIG. 1 and FIG. 9 is for illustrative purposes only and forms no part of the claimed design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof;

FIG. 7 is a bottom plan view thereof; and,

FIG. 8 is a perspective view thereof.
